AUTOMATIC REGULATOR FOR FURNACES AND THE LIKE

Filed Feb. 10, 1925

Fig. 3.

by Alexander S. Lunt.
His Attorney.

UNITED STATES PATENT OFFICE.

THEODOR STEIN, OF BERLIN-FRIEDENAU, GERMANY, ASSIGNOR TO GENERAL ELECTRIC COMPANY, A CORPORATION OF NEW YORK.

AUTOMATIC REGULATOR FOR FURNACES AND THE LIKE.

Application filed February 10, 1925, Serial No. 8,217, and in Germany March 7, 1924.

In automatically acting regulating devices, such as are ordinarily met with, there are usually involved processes wherein the quantity or magnitude to be controlled, regulated or adjusted, bears a definite relationship to the quantity which acts on the regulator. In such cases, therefore, each and every position of the regulator corresponds to a definite value of the quantity to be regulated. 10 However, there exists processes wherein such definiteness of relationship between the quantity or magnitude to be controlled and the quantity which acts on the regulator does not obtain, and my invention is directed especially to this type of process. 15

A process of this latter type and one to which my invention is well adapted is that met with in firing a furnace such as the furnace of a steam boiler, wherein the supply of air and fuel to the furnace is automatically controlled. In a mechanical furnace stoker which is to work automatically, it is necessary, on the one hand, to regulate the fuel supply in conformity with the load, 25 while, on the other hand, the supply of air for combustion must be regulated in accordance with the fuel supply, the relationship between the quantity of air and the quantity of fuel having to be chosen so that the chimney loss, that is, the amount of energy going to waste with the flue gases is made as small as possible. If the excess of air over and above the quantity theoretically required for combustion is too small, it is well known 30 that the chimney loss grows because with the flue gases there escapes an unduly large quantity of fuel portions that have not been burned up at all or only imperfectly so. If, on the contrary, the excess of air is too great, it is known that for its heating there is consumed an unduly large amount of the heat developed, and this passes into the waste or flue gases. Between quantity of air and the chimney loss there exists, therefore, at any instant, a definite volume of air which corresponds to a minimum value of chimney loss and with any change from this volume of air either by way of increase or decrease there results an increase in the 50 chimney loss.

The definite volume of air corresponding to minimum value of chimney loss varies with the amount of fuel, and with the qual-

ity of the fuel and there exists no definite relation of the ratio between air volume and fuel supply for various values of fuel supply. This is illustrated in the drawing wherein Fig. 1 is a set of curves; Fig. 2 is a diagrammatic view of a system embodying my invention; and Fig. 3 is a diagrammatical illustration of a detail of Fig. 2 on a slightly enlarged scale. 55

Referring to Fig. 1, the line or curve A illustrates the dependence of the chimney loss V upon the volume of air L for a definite load and nature of fuel and in connection with curve A it will be noted that there is a point 1 which represents the volume for minimum chimney loss value, the chimney loss value increasing with either increase or decrease of the quantity of air from such volume. This point 1 may be termed the "reversal point" of the curve and indicates the value of the quantity of air to be maintained for minimum chimney loss under the particular operating conditions. As the operating conditions change, the location of the point corresponding to point 1 changes, points corresponding to other conditions being those indicated at 2 and 3 on curves B and C. These points 1, 2 and 3 indicate therefore, values of air flow to be maintained under different operating conditions in order to operate with minimum chimney loss. 65

Referring now to Fig. 2, 5 indicates a regulating means for regulating the supply of fuel to a furnace and 6 indicates a regulating means for regulating the supply of air to the furnace. These regulating means may take any desired form and are indicated only diagrammatically in the drawing. They are connected by stems 7 and 8 to a lever 9, one end of which is connected to the lower end of a threaded rod 10. Stem 7 is pivotally connected to lever 9 providing a fulcrum at 11 and it is provided with an extension 12 which is connected to a piston 13 located in a cylinder 14. When piston 13 moves it adjusts the fuel regulating means 5 and the air regulating means 6 in the same sense, increasing and decreasing both supplies together. Piston 13 and cylinder 14 represent a device movable in accordance with an operating condition of the furnace 100 for adjusting the fuel and air in accordance 105

with the demand. For example, piston 13 may be subjected to the boiler pressure through a pipe 15, whereby the furnace will be regulated to maintain constant boiler pressure.

5 Rod 10 is threaded into the hub of a worm wheel 16 supported on a base 16^a and it will be seen that when worm wheel 16 is turned in one direction or the other, rod 10 will be 10 raised or lowered thereby turning lever 9 on fulcrum 11. This it will be seen, adjusts the air regulating means 6 but does not move the fuel regulating means 5. Meshing with worm wheel 16 is a worm 17 which is driven 15 by an electric motor 18 of the reversing type. Motor 18 is connected by an electric circuit 19 to a magnetically operated reversing switch 20. In circuit 19 is a source of electrical energy 21. Motor 18 is a continuously running motor, and switch 20 serves to reverse the connections to the motor to determine the direction of rotation. Switch 20 may 20 be of any suitable type. For example, it may be of the segmental drum and ratchet 25 type which turns always in the same direction and upon each movement reverses the connections on the motor, as indicated at 20^a, Fig. 3, the magnetic operating means therefor being indicated at 20^b.

30 The magnetic operating means of the present example is of the well known differentially connected type having two sections which balance each other magnetically when energized equally and at the same time, and 35 either of which will operate the switch when separately energized.

With this arrangement, if the switch has 40 been operated by energizing one section of operating means 20^b and said section is still energized, the switch will be moved or operated if the other section is momentarily energized. This neutralizes the magnetic pull of the first-named section and permits the ratchet mechanism 20^a to reengage in 45 readiness to advance the switch when the second section is again deenergized and the neutralizing effect thereof is removed from the first section. If either section of the magnetic operating means has been energized to operate the switch and then immediately deenergized, it will be seen that the switch will also be advanced upon subsequently energizing the other or the same section so that the switch will in all cases 50 be advanced to effect a reversal of motor 18 upon energizing either section or upon energizing and deenergizing one section while the other is energized.

60 This is only one type of commonly known magnetically operated reversing switch, and as the particular type of switch is not essential to the invention, further description is believed to be unnecessary. Connected to switch 20 is an operating circuit 22 which 65 contains a source of electrical supply 23 and

has its terminals connected to two contacts 24 and 25 which together form a circuit closer. These contacts are in circuit with and control one section of the magnetic operating means.

70 The circuit closer comprising contacts 24 and 25 is controlled by means responsive to the chimney losses in any suitable manner and by any suitable means, the arrangement being such that when the chimney losses exceed a predetermined value, the circuit is closed. Any suitable type of device which measures the chimney losses or which operates in response to changes therein may be utilized. Suitable devices for this purpose 75 may be provided for any particular installation and do not per se concern the present invention. In the present example, the contact 25 is connected to the plunger 26 of a solenoid having a winding 27 in which a flow 80 of current is effected in accordance with the chimney loss value, or with some determining factor thereof. Current flows continuously through winding 27 and has a certain minimum value when the chimney losses are 85 a minimum. When the chimney losses increase the flow of current increases. When the flow of current increases due to increase in chimney losses the solenoid plunger 26 is moved upward to bring contact 25 into engagement with contact 24 thereby closing the circuit on the magnetically operated reversing switch 20. Contact 24 is carried by the movable element 28 of a dash-pot 29. The dash-pot normally holds contact 24 stationary but permits it to move upward when the pull of the solenoid or its plunger increases 90 somewhat, due to increase in chimney losses. Upon decrease in chimney losses, plunger 26 moves downward away from contact 24 and 95 into engagement with the head which carries contact 24. The weight of the plunger is then sufficient to move contact 24 downward until a balanced position is reached. Contact 24 is thus a floating contact and 100 can be moved up or down by the movement of plunger 26. Plunger 26, of course, assumes a position corresponding to the extent to which solenoid winding 27 is energized. In connection with circuit 22 there is provided also a time-controlled circuit closer 105. This is placed in circuit with the remaining section of the magnetic operating means.

110 The operation is as follows:

115 Motor 18 runs continuously in either one direction or the other thus continually increasing or decreasing the supply of air through the operation of worm wheel 16, threaded rod 10, lever 9 and stem 8, the lever 120 9 turning on fulcrum 11. Assume a load condition wherein the relation to chimney loss of volume of air is represented by the curve A which represents minimum chimney loss. The air supply is thus regulated to 125 maintain efficient operating conditions. At 130

the same time, the fuel and air supply may be automatically regulated together by the means which responds to the demand on the furnace.

5 In connection with the foregoing, assume that the contact 24 has just caused operation of the change-over switch 20 so that the motor 18 is being driven in a direction to diminish the air supply; in other words, that 10 the point 4 on curve A has just been reached and the circuit closed. Assume further that as a consequence of variation of the fuel the combustion processes no longer take place in accordance with characteristic curve A 15 but instead in conformity with the characteristic curve B which has a reversal point located at 2. To point 4 on curve A there corresponds a point 4^a on curve B. A comparison of curves A and B indicates that 20 while the quantity of air supplied at point 4 on curve A represents excess air, the same quantity when supplied on curve B represents too little air. It follows, therefore, that since motor 18 has been reversed at 25 point 4 to reduce the air volume, the condition exists that, owing to the fact the operation is now taking place according to curve B, the motor will be operating in the wrong direction to move the volume toward point 30 2 on curve B. In other words, while according to curve B the motor should be operating in a direction to increase the air supply, it is actually operating in a direction to decrease it. As a result, the chimney loss 35 measuring device would keep on increasing and contact 25 would remain closed. The result would be a continual impairment of conditions. In order to avoid an occurrence of this character, the time-controlled reversing switch 30 is provided. This time-controlled reversing switch which, as already 40 stated, may be of any suitable type, operates automatically to reverse the direction of rotation of motor 18 at certain definite intervals of time and entirely independently of the position of the magnetically operated reversing switch 20 and the device 26. As 45 a result, even if conditions just set forth occur the time-controlled reversing mechanism will after a predetermined period automatically reverse motor 18 and correct the operating conditions.

50 As already stated, any suitable type of device for measuring the chimney loss may be utilized to actuate the circuit closer in circuit 22, the essential thing being that the circuit be closed upon the occurrence of chimney losses in excess of a predetermined amount. In the present instance, the provision of the dash pot in connection with contact 24 effects the result that the circuit closer does not respond to an absolute quantity or a definite value of the chimney loss but, due to the fact that it enables contact 24 to 55 assume different positions, rather to the cir-

cumstance that a change in the sense that an increase in the quantity of chimney loss takes place.

In accordance with the provisions of the Patent Statutes, I have described the principle of operation of my invention, together with the apparatus which I now consider to represent the best embodiment thereof, but I desire to have it understood that the apparatus shown is only illustrative and that the invention may be carried out by other means. 70

What I claim as new and desire to secure by Letters Patent of the United States, is:—

1. In a furnace control apparatus, the combination with means responsive to the load on the furnace for automatically regulating the supply of fuel and air to the furnace, of continuously operating means for varying the air supply, and means responsive to changes in chimney losses for reversing 80 the direction of operation of said continuously operating means.

2. In a furnace control apparatus, the combination with means responsive to the load on the furnace for automatically regulating the supply of fuel and air to the furnace, of continuously operating means for varying the air supply, means responsive to changes in chimney losses for reversing 90 the direction of operation of said continuously operating means, and periodically operated time-controlled means for reversing the direction of operation of said continuously operating means.

3. In a furnace control apparatus, the combination with means responsive to the load on the furnace for automatically regulating the supply of fuel and air to the furnace, of continuously operating means for varying the air supply, a magnetically operated reversing switch for reversing the direction of operation of said continuously operating means, a circuit closer for effecting operation of said reversing switch, and means for actuating said circuit closer whenever the chimney losses depart from a predetermined value. 100

4. In a furnace control apparatus, the combination with means responsive to the load on the furnace for automatically regulating the supply of fuel and air to the furnace, of continuously operating means for varying the air supply, a magnetically operated reversing switch for reversing the direction of operation of said continuously 105 operating means, a circuit closer for effecting operation of said reversing switch, means for actuating said circuit closer whenever the chimney losses depart from a predetermined value, and periodically operated time-controlled means for reversing the direction of operation of said continuously operating means. 115

5. The combination with a furnace, of 120 means for controlling the supply of air 125

thereto, continuously operating means for regulating said controlling means, and means responsive to changes in chimney losses for reversing the direction of operation of said continuously operating means.

6. The combination with a furnace, of means for controlling the supply of air thereto, continuously operating means for regulating said controlling means, means re-

sponsive to changes in chimney losses for reversing the direction of operation of said continuously operating means, and periodically operated time-controlled means for reversing the direction of operation of said continuously operating means.

In witness whereof, I have hereunto set my hand this 22nd day of January 1925.

THEODOR STEIN.
